UNITED STATES PATENT OFFICE.

MILDRED LEWLESS, OF NEW YORK, N. Y.

PORTABLE RADIATOR-HEATER.

Specification of Letters Patent.

Patented July 7, 1914.

1,102,934.

Application filed January 23, 1914. Serial No. 814,925.

To all whom it may concern:

Be it known that I, MILDRED LEWLESS, a citizen of the United States, and a resident of the city of New York, borough of Brooklyn, in the county of Kings and State of New York, have invented a new and Improved Portable Radiator-Heater, of which the following is a full, clear, and exact description.

The present invention comprehends the provision of a portable radiator heater, the device being adapted to receive any improved form of radiator having suitable means for supplying water thereto and carrying a burner for heating the water or generating steam for heating purposes.

A further object of the invention is comprehended in the provision of a radiator heater which embodies a novel form of base or receiving compartment for a radiator and which incloses such part of the latter as to produce a maximum quantity of heat with a minimum of fuel by permitting the proper portion of the radiator sections to be inclosed or subjected to the action of the heating medium to secure a maximum amount of heat radiation from the remaining portion which is exposed.

With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

Reference is to be had to the accompanying drawings forming a part of this specification, in which similar characters of reference indicate corresponding parts in all the views, and in which—

Figure 1 is a vertical longitudinal sectional view of my improved portable radiator heater having a radiator mounted therein; Fig. 2 is a vertical sectional view taken on the line 2—2 of Fig. 1 and looking in the direction of the arrow; Fig. 3 is a detail perspective view of a portion of the base or compartment forming a part of the heater; and Fig. 4 is a perspective view of the component parts forming the bottom of the base or compartment, showing the construction of the main bottom and the auxiliary bottom which is suspended therefrom.

In illustrating the use and application of the invention I have shown a radiator 10 which comprises a series of sections 11, the

radiator being connected to any suitable source of water supply and having the usual legs 12 by which it is supported. The sections are also connected in any preferred manner by a pipe connection 13 through which water is supplied to the various sections forming the component parts of the radiator constituting a part of a heating system or a complete heating system in itself, although the present device is more particularly adapted for application to radiators which have no connection with a common water supply system.

The device comprising the invention consists of a portable base or compartment 14 of substantially rectangular shape and made of metal. In the drawings the same is shown as being made of a rectangular shell of sheet or cast metal having slightly inclined side portions 15 and end portions 16 which are provided with spaced apertures 17 for anchoring the device to the usual connecting bolts 18 of the radiator sections. The connection of the base to the radiator is not essential and may be omitted without departing from the spirit of the invention. The upper longitudinal edges of the side portions 15 are provided with spaced extensions 19 which are adapted to extend between the radiator sections in the manner shown in Figs. 1 and 2 of the drawings, with certain of the extensions bent around the connecting bolts 18, as shown at 20. By this means the base member is more positively anchored against movement or shifting with respect to the radiator as an entirety, but the essential purpose of the extensions 19 is to close the spaces between the radiator sections to prevent the escape of heat generated as energy beneath the hollow sections of the radiator and thus to cause a maximum heating of the water or generation of steam for heating purposes.

The sides 15 are also provided with inwardly extending flanges 21 and secured to each end wall 16 transversely of the latter at their lower edges is an end flange or angle piece 22, the same having feet 23 depending therefrom to be located approximately beneath the extremities or tread portions of the legs 12 of the radiator so as to withstand or support the weight of the latter without materially bearing upon the base itself. In this manner the material forming the base may be made very light and thus the device can be more economically manufactured.

Previous to the mounting of the radiator within the base and after the attachment of the angle pieces 22 to the ends thereof as by riveting or otherwise, a bottom plate 24 is fitted in the base or compartment forming the shell of the heater so as to rest upon the horizontal portion of the angle pieces and the flanges 21. The base, however, has its intermediate longitudinal edges severed, as shown at 25, to provide end extensions 26 which rest upon the flanges 21 while the intermediate portions are bent upwardly, as shown at 27, to provide side openings with which the bendable or flexible portions 27 coöperate to form draft regulators or means to control or regulate the draft or supply of air to the combustion chamber beneath the radiator, by varying the widths of the openings between the parts 27 and the sides 15 of the base.

The burner is indicated by the numeral 2 and consists in the present instance, for purposes of illustration, of a pipe or tube having suitable burner openings 28' for the escape of the fuel, the combustion of which is properly supported by the air entering the draft openings. The numeral 29 indicates any form of thermostatic or pressure valve which is connected to the pipe section 13 to communicate with the interior of the radiator sections and is adapted to coöperate with a valve 30 interposed in the supply pipe 31 which leads to a mixing chamber 32 communicating with the burner 28. The supply of fuel through the pipe 31 and into the mixing chamber is regulated by a valve 33 which is preferably of the needle type. The casing of the diaphragm or other valve 29 communicates with the pipe section 13 as is obvious, so that the radiator if not connected to a common water supply system may be supplied with water through a filling cup 34, the inlet pipe being capable of being opened or closed by means of a valve 35. A glass gage 36 also communicates with the upper and lower portions of the diaphragm casing for the purpose of determining the height of the water in the radiator.

As before mentioned, the up-turned portions 27 constitute draft regulators or valves 50 cooperating with the spaces between the longitudinal edges of the bottom 24 and the sides 15, and these valves are adapted to be bent inwardly or outwardly or otherwise 55 moved for restricting or increasing the sizes of the draft openings to supply the proper quantity of air or oxygen to the combustion chamber. The heat generated in the chamber, however, is quite extreme and it is necessary 60 to provide some means to obviate the heating of the floor due to the relatively low position of the bottom of the heater. For this purpose an auxiliary bottom 37 is provided, the same consisting of a metal section 65 having up-turned side portions 38

which at their upper edges have hooked or inwardly extending re-bent portions 39.

The auxiliary bottom 37 corresponds in length to the length of the incisions in the longitudinal edges of the bottom 24, or in other words, the lengths of the draft openings and the valves or regulators therefor, so that the inturned portions 39 will engage over the upper edges of the parts 27 to suspend the auxiliary bottom in the manner shown in Figs. 1 and 2 of the drawings and thus provide an air space 40 between the main and auxiliary bottoms with its sides closed and its ends open and opposite and distinct from the openings provided in the sides of the main bottom. In this manner benefit is derived from the full amount of air present at the sides of the radiator without dividing the same to partly enter the cooling space between the main and auxiliary bottoms and a cool and complete current of air is supplied through the cooling space. Since gas, kerosene, gasoline or any other kind of fuel may be used with the improved heater, as distinguished from coal burning heaters, there will be a minimum of dirt caused as well as time and care in looking after the device, and the cost of maintenance will also be minimized.

Having thus described my invention, what I claim as new and desire to secure by Letters Patent is:—

1. A portable radiator heater adapted for application to ordinary radiators having the usual legs, comprising a casing adapted to 100 removably inclose and support the lower portion of a radiator therein, and a burner mounted in said casing between said legs.

2. A portable radiator heater adapted for application to ordinary radiators having supporting legs, comprising a casing adapted to inclose the legs and lower portion of a radiator, supports for said casing upon which the radiator legs are adapted to rest whereby the radiator is supported in spaced relation to the floor, a burner extending longitudinally of the casing and supported in the ends thereof beneath said radiator, and means for controlling the supply of fuel to the burner.

3. A portable base for radiators having supporting legs, comprising a casing having closed side and end walls, extensions carried by the casing for disposal between the sections of the radiator to close the spaces there-between, said radiator being provided with supply means for water, means for supplying heat to the casing beneath the radiator, and a bottom for the base having end flanges upon which said radiator is supported through the instrumentality of said legs.

4. A portable heater of the class described, comprising a casing of substantially rectilinear contour, having open top and bottom portions, means at the top portion of the 130

casing to form a tight joint with a water-carrying element mounted in the casing, feet for the casing near the ends thereof to sustain the weight of the element, means above 5 the feet to sustain and carry the radiator, and a bottom for the casing having side draft openings.

5. A portable heater of the class described, comprising a casing of substantially rectilinear contour having open top and bottom portions, means at the top portion of the casing to form a tight joint with a water-carrying element mounted in the casing, feet 10 for the casing near the ends thereof to sustain the weight of the element, flanges attached to the ends of the casing and carrying said feet, a main bottom supported upon said flanges between the element and the flanges, said bottom having up-turned side 15 portions producing draft openings and regulators therefor, and an auxiliary bottom suspended from said up-turned portions in spaced relation to the main bottom.

6. A portable heater of the class described, comprising a casing of substantially rectilinear contour having open top and bottom portions, means at the top portion of the casing to form a tight joint with a water-carrying element mounted in the casing, feet 20 for the casing near the ends thereof to sustain the weight of the element, flanges attached to the ends of the casing and carrying said feet, a main bottom supported upon said flanges between the element and the flanges, said bottom having up-turned side 25 portions producing draft openings and regulators therefor, an auxiliary bottom in spaced relation beneath said main bottom to provide

an air space and having ~~upturned~~ ^{upturned} sides closing said space adjacent to the draft openings, 40 the ends of said space being open to permit the circulation of air therethrough independently of the draft openings aforesaid, and a heating medium carried by the casing between said draft openings.

7. The combination with a radiator, comprising a series of spaced sections and connecting means for said sections, said radiator having supporting legs; of a casing snugly fitting around the lower portion of the radiator and removably connected to said section-connecting means, means for supplying water to the radiator sections, a series of spaced extensions at the sides of the casing disposed between said sections, said sides 50 having inturned flanges at the lower edges, inwardly extending supports at the ends of said casing upon which the radiator legs rest, a burner extending through the casing and supported in the ends thereof beneath the radiator, and a double bottom supported upon the flanges and inwardly extending supports at the bottom of the casing, said bottom having draft openings at the sides 55 for supplying air to the combustion chamber beneath the radiator, and openings at the ends for supplying air between the portions of the double bottom beneath said combustion chamber.

In testimony whereof I have signed my name to this specification in the presence of two subscribing witnesses.
